UNITED STATES PATENT OFFICE.

HENRY H. HOOPS, OF WEST SAVANNAH, GEORGIA.

OIL-BURNER.

1,233,359.

Specification of Letters Patent. Patented July 17, 1917.

Application filed February 28, 1917. Serial No. 151,493.

To all whom it may concern:

Be it known that I, HENRY H. Hoops, a citizen of the United States of America, residing at West Savannah, Chatham county, 5 Georgia, United States of America, have invented certain new and useful Improvements in Oil-Burners; and I do hereby declare the following to be a full, clear, and exact description of the invention, such as 10 will enable others skilled in the art to which it appertains to make and use the same, reference being had to the accompanying drawings, and to letters or figures of reference marked thereon, which form a part of this 15 specification.

My invention relates to oil burners in which the oil is projected from the burner by means of steam, and more particularly to that type of burner in which the steam projects the oil over a platform at the discharge end of the burner to obtain subdivision or spraying of the oil into a furnace chamber or other chamber to be heated.

Referring to the accompanying drawings, 25 in which like parts are similarly designated—

Figure 1 is a plan view of a burner embodying my invention.

Fig. 2 is a side view thereof.

Fig. 3 is a longitudinal section on line 30 3—3 of Fig. 1.

Fig. 4 is an end view.

Fig. 5 is a cross section on line 5—5 of 35 Fig. 1.

Fig. 6 is a cross-section on line 6—6 of Fig. 1.

Fig. 7 is a cross section illustrating a 40 modification.

Conveniently the burner is made in three 45 parts, comprising a steam chamber 1, having a steam inlet 2 and an oil chamber 3 provided with an oil inlet 4 adjacent to which is a clean out, closed by a plug 5. The two chambers are separated from one 50 another by an interposed plate 6, and bolted or screwed together by screws 7. Both chambers discharge onto the platform, the steam chamber through a port 8 larger than the discharge port 9 of the oil chamber.

Such a construction of the body of the 55 burner is known; my invention consists in a particular construction of the platform.

The object of my invention is to better 55 distribute the oil throughout the furnace chamber to obtain a better heating of the chamber and at the same time obtain a bet-

ter combustion, thereby materially increasing the efficiency of the burner.

It will be observed that the platform is curved at its discharge end 10^a, thereby effecting the discharge from the several spraying elements terminating at this end at different points, as will be hereinafter explained.

The platform also widens from an apron 65 9^a of the oil discharge orifice to the curved or semicircular end 10^a. The apron 9^a is parallel to the plate 6 to provide a longitudinally directed oil port 9.

Along the middle of the platform I provide a groove 11, preferably having an upward incline from the oil discharge port 9 to the middle of the curved portion, as shown. This groove 11 is preferably deeper and wider than the grooves 12 that are arranged one at each side of said groove 11. The grooves 12 are preferably inclined to a greater degree than the groove 11, so that they terminate at the curved end of the platform at a higher level, Fig. 4.

The grooves 11 and 12 are rectangular, or substantially so, in cross section, and located between them are channels 13 terminating in upwardly directed lips 14. These channels 13 have substantially the same inclination as the channels 12, but differ from them in being curved in cross-section. Their side walls 13^a at the port 9 are on the same level as the apron 9^a.

The outer sides of grooves 12 are formed 90 by the beveled sides 15 of the platform. These sides project above the other elements of the platform and have beveled faces 16.

The operation is as follows:

Steam and oil are supplied through the respective inlets 2 and 4 to the respective chambers 1 and 3, as is customary with this type of burner. The oil discharges from the oil port 9 over the apron 9^a onto the platform and is driven over the platform by the 100 steam issuing from the steam port 8.

The middle, wider and deeper groove 11 carries the largest quantity of oil to the most extreme point of the curved end 10 of the burner at the lowest level. Other streams 105 are carried and directed by the grooves 12 at an angle to the stream in groove 11, to the front of the burner. Oil also passes along the grooves 13 and is projected upward and away from the platform by striking the inclined walls of the upwardly directed lips 14 at the ends of said grooves.

The beveled faces 16 of the sides 15 direct the oil laterally and upwardly.

The result is that the flame area assumes somewhat the shape of a quadrant of a sphere, and thus is well suited for use in the fire boxes of locomotives and other engines.

In Fig. 7 I have shown the grooves 11^a and 12^a as undercut. They thus carry a greater quantity of oil, and carry a very much larger quantity to the end of the platform, so that the streams issuing from the platform will be projected farther from the platform before being broken up by the steam. The undercuts prevent too large a part of the oil from being spread from them laterally over the platform by the high pressure steam.

The sides of the platform are also made higher than in Figs. 1-6, and instead of having plain beveled oil-dispensing surfaces, they are shown slightly curved as at 16^a, so as to present a surface of beveled type but somewhat steeper than the surface 16. Such a structure is preferable where the fire box is long, as the flame produced by such a burner is more elongated.

I claim—

1. In an oil burner having a steam chamber and an oil chamber and a platform onto which said chambers discharge, the improvement which comprises providing longitudinally directed oil conducting grooves in said platform.

2. In an oil burner having a steam chamber and an oil chamber and a platform onto which said chambers discharge, the improvement which comprises providing oil conducting grooves in said platform differently inclined.

3. In an oil burner having a steam chamber and an oil chamber and a platform onto which said chambers discharge, the improve-

ment which comprises providing oil conducting grooves in said platform and having undercut sides.

45

4. In an oil burner having a steam chamber and an oil chamber and a platform onto which said chambers discharge, the improvement which comprises providing oil conducting grooves in said platform terminating at upwardly directed lips.

50

5. In an oil burner having a steam chamber and an oil chamber and a platform onto which said chambers discharge, the improvement which consists in providing divergent sides to said platform, said divergent sides forming sides of lateral longitudinally directed oil conducting grooves in said platform.

55

6. In an oil burner having a steam chamber and an oil chamber separated by a plate, and a platform onto which said chambers discharge, the improvement which consists in providing an apron parallel to said plate to form the oil port and a plurality of 65 grooves of different lengths in said platform extending from said apron along the platform.

60

7. In an oil burner having a steam chamber and an oil chamber separated by a plate, and a platform onto which said chamber discharges, the improvement which consists in providing a curved end for the platform wider than its receiving end, a plurality of longitudinally directed end discharging 75 grooves of different inclination, grooves terminating in upwardly directed lips, and beveled sides for said platform, and an apron parallel to said plate for directing oil into said grooves.

70

In testimony that I claim the foregoing as my invention, I have signed my name.

80

HENRY H. HOOPS.
